UNITED STATES PATENT OFFICE.

JOSEPH W. JONES, OF NEW YORK, N. Y.

DESIGN FOR AN AUTOMOBILE-HORN.

No. 40,186.

Specification for Design.

Patented July 27, 1909.

Application filed May 12, 1909. Serial No. 495,570. Term of patent 3½ years.

To all whom it may concern:

Be it known that I, JOSEPH W. JONES, a citizen of the United States, and a resident of the city, county, and State of New York, (whose post-office address is Broadway, at Seventy-sixth street, New York city, New York,) have invented a new, original, and ornamental Design for Horns for Automobiles, which design is fully set forth in this specification, reference being had to the an-

nexed drawing, forming part hereof, which is a side view of a horn embodying my invention.

I claim:

The ornamental design for an automobile horn, as shown.

JOSEPH W. JONES.
